ENGINE STARTER

John B. Hiday, Anderson, Ind., assignor to General Motors Corporation, Detroit, Mich., a corporation of Delaware

Application April 30, 1949, Serial No. 90,620

4 Claims. (Cl. 290—38)

1

This invention relates to engine starting apparatus comprising an electric motor driving a pinion engageable with a gear of the engine and manually controlled means for effecting gear engagement and for controlling the motor.

An object of the invention is to provide for the control of the motor to effect initial rotation of the pinion to facilitate meshing thereof with the engine gear and to provide for the application of current to the motor sufficient for engine cranking only after the pinion and gear are substantially in mesh. In the disclosed embodiment of the invention, the structure includes two available push button switches located in tandem relation and mounted so that the application of pressure in the direction to close one of the switches causes the closed switch to move bodily to effect closure of the second switch provided the pinion driven by the electric motor is substantially in mesh with the gear of the engine to be started. The closing of the first switch connects a current source with the electric motor through a resistance so that the motor may turn the pinion initially with low torque and speed to facilitate meshing the pinion with the flywheel gear. The closing of the second switch by bodily movement of the first switch causes this resistance to be short-circuited so that the electric motor receives full cranking current.

Further objects and advantages of the present invention will be apparent from the following description, reference being had to the accompanying drawing, wherein a preferred embodiment of the present invention is clearly shown.

In the drawing:

Fig. 1 is a side view partly in section of the engine starting apparatus embodying the present invention, the parts in section above the motor being taken on line 1A—1A of Fig. 4, and the other parts in section being taken on the line 1B—1B of Fig. 2.

Figs. 2 and 3 are views in the direction of arrows 2 and 3, respectively, of Fig. 1.

Fig. 4 is a view in the direction of arrow 4 showing the switch structure.

Fig. 5 is a fragmentary, sectional view on the line 5—5 of Fig. 2 and is drawn to a larger scale.

The starting motor has a cylindrical field frame 10 attached to end frames 11 and 12 which support an armature shaft 13 (Fig. 2) connected with a small gear 14 which meshes with a larger gear 15 having a hub 16 which is attached to a shell 17 providing the driving member of a one-way clutch having rollers 18 and a driven member 19 attached to the hub 20 of a pinion 21. A

cover 17a attached to shell 17 secures the clutch parts together. Hub 20 receives bearings 22 journaled on a fixed rod 23 attached to a frame 23a. The hub 16 is attached to a tubular member 24 passing through a hole 25 in frame 12 and through a seal 26. Member 24 encloses a spring 27 confined under pressure between the left end member 24 and a cup 28 which the spring urges against the left end of the rod 23. Therefore the assembly of the parts slideable on the rod 23 is urged left into the position shown in Fig. 1 by the spring 27 so that the pinion 21 is normally out of mesh with the gear 30 connected with the engine to be started. The gearing is enclosed by housing 32 attached to frame 23a. The housing 32 has an opening for receiving a circular flange 33 provided by the frame 12 and the frame 12 is secured to housing 32 by screws 34. The field frame 10 receives screws 35 upon which the bifurcations of a lever 36 are pivoted. Lever 36 provides a projection 37 engageable with the left end of the member 24. Therefore counterclockwise rotation of lever 36 effects movement right of member 24, gear 15, the overrunning clutch and pinion 21.

Lever 36 is connected by pins 38 and links 39 with a plate 40 which is shaped to receive the button 41 of a push button switch SW1 having a metal case 42 which supports contacts 43 provided by the heads of terminal screws 44 insulated from the case and receiving nuts 45 by which lock washers 46, plain washers 47 and the ends of resistances 48 are secured to the switch case. The button 41, which is guided by a sleeve 49 attached to the cover 50 of case 42, is attached to a rod 51 surrounded by a spring 52 confined under compression between the cover 50 and a washer 53 attached to the rod. The rod is guided by flange 54 of cover 50 and has a reduced portion 55 which receives non-conducting washers 56, 57, 58 and 58' which support a contact 59 engageable with contacts 43. A washer 60 attached to rod 51 retains the contact 59 and its insulating washers. When button 41 is released, the spring 52 urges the rod 51 right to cause the washer 60 to press the washer 58' against the inside of the cover 50.

A second switch SW2 constructed like switch SW1 is located in tandem relation therewith. Tubular members 61 having threaded shanks 62 extending through the cover 50 of switch SW2 receive nuts 63 by which the members 62 are attached to cover 50 of switch SW2. The members 61 receive rods 64 having shoulders 65 and threaded shanks 66 which receive nuts 67 by

which the rods 64 are attached to the cover 50 of switch SW1. Flanges 68 of a yoke 69 are clamped between the shoulders 65 and the cover 50 of the switch SW1. The yoke 69 includes a plate 69a adapted to engage the end of rod 51 of switch SW2. The switch SW2 is connected with motor end frame 11 by flexible strap 70. A spring 71 confined under compression between the cover 50 of switch SW2 and the plate 69a of yoke 69 urges the switch SW1 away from the switch SW2 and lever 36 clockwise into engagement with a stop pin 80 (Fig. 1) attached to motor field frame 10. The left ends of resistance coils 48 are attached to the terminal screws 44 of switch SW2 by the tightening of nuts 45 which secure also terminal clips 72 and 73 of wires 74 and 75 respectively. Wire 74 is connected with the non-ground terminal of a current source (not shown), and wire 75 is connected with terminal 76 of the starting motor whose other terminal is grounded.

The operation of the apparatus is as follows: Lever 36 is moved counterclockwise to effect the closing of the switch SW1 which causes current to flow from the source through the resistance coils 48 to the electric motor so that the motor operates initially with relatively slow speed and torque to cause the pinion 21 to rotate as it is moved into engagement with the gear 30. In case of gear tooth abutment, the torque produced by the motor may not be sufficient to turn pinion 21 while abutting the gear. Therefore counterclockwise movement of lever 36 is arrested. Lever 36 is released and it returns to engagement with the stop 80 and switch SW1 opens. Lever 36 is moved counterclockwise again to mesh the pinion with the gear. Generally this can be done after at least the second movement of the lever, since the pinion has turned before contact with the gear into a position different from the preceding one which caused tooth abutment. The meshing of the pinion 21 with the gear 30 permits further counterclockwise movement of lever 36 so that the closed switch SW1 moves bodily to the left to cause the plate 69a of yoke 69 to engage the rod 51 of switch SW2 and to effect closure of that switch causing its terminals 44 to be connected thereby short-circuiting the resistance coils 48 and applying cranking current to the starting motor.

When the engine becomes self-operative and tends to drive the pinion 21 faster than it can be driven by the electric motor, pinion 21 overruns shell 17 connected with gear 15. When lever 36 is released, the contact opening springs 52 of the switches SW1 and SW2 and the spring 71 are permitted to expand so that the switches are opened and lever 36 moves clockwise against the stop pin 80.

In the normal position of lever 36, there is space (Fig. 1) between its projection 37 and the member 24 whose normal position is determined by engagement of gear hub 16 with the seal 26. The sum of the normal space between the projection 37 of lever 36 and the member 24 and the normal space between the pinion 21 and the gear 30 is sufficient to permit closing switch SW1 before the pinion contacts the gear. Therefore the pinion is rotating as it closely approaches the gear.

While the embodiment of the present invention as herein disclosed, constitutes a preferred form, it is to be understood that other forms might be adopted.

What is claimed is as follows:

1. Engine starting apparatus comprising an electric motor, a pinion driven thereby and movable axially into engagement with a gear connected with the engine, two spring opened switches having actuators and placed in tandem relation, the first switch being bodily movable relative to the second switch to effect operation of the actuator of the second switch to close it, a spring which opposes bodily movement of the first switch toward the second switch so that the first switch is closed before it causes operation of the actuator of the second switch to close it, each switch having a pair of terminals, one terminal of the second switch being connected with the motor and the other terminal being connectible with the current source, a circuit connected with the terminals of the second switch and including a resistance and the terminals of the first switch, and a movable control member for pressing the actuator of the first switch to close it and thereafter for causing engagement of the pinion with the gear and causing, by movement of the first switch bodily, the closing of the second switch to short circuit the resistance and to connect the motor directly with a current source provided the pinion has been meshed with the gear, abutment of teeth of the pinion with teeth of the gear preventing operation of the member to close the second switch.
2. Engine starting apparatus according to claim 1 in which the second switch is supported by the frame of the motor and in which means attached to the second switch supports the first switch and guides it for movement bodily relative to the second switch.
3. Engine starting apparatus according to claim 1 in which the second switch is attached to the frame of the motor, and in which the second switch supports the first switch through the medium of telescopically engaging members attached, respectively, to the switches.
4. Engine starting apparatus according to claim 1 in which the second switch is attached to the frame of the motor, in which there are two spaced sets of telescopically engaging members, one each of the members of the sets being attached to one switch and the other members to the other switch, in which the resistance is provided by two spaced helical coils of wire, the axes of the coils and axes of the sets of members being parallel to the direction of movement of the switch actuators, and the axes of the coils being in a plane at right angles to the axes of the sets of telescopically engaging members.
